LOAD HANDLING AND ENGAGING DEVICE
FOR LIFT TRUCKS

Jack N. Garrett, McGregor, Tex.

Application August 16, 1951, Serial No. 242,050

4 Claims. (Cl. 214—730)

1

This invention relates to a load engaging and carrying attachment adapted to be used with the ordinary commercial lift truck. This device is particularly useful in handling bulk materials, such as cotton bales.

In the storage and handling of baled items it is desirable that the identification on each bale be visible so as to aid in the inventory and shipment of same. Naturally, it is advantageous to store as much as possible in a given area. It has been generally found that this can best be accomplished by stowing one bale on top of another and leaving sufficient working aisles so that one side of each bale is exposed.

In utilizing this type of warehousing it has been found that a great deal of floor space was wasted in aisle spaces. It appears that the ordinary lift truck requires a very wide passageway for stowing bales in this manner because it is necessary to turn the truck crosswise in the aisle to place the bales in position. To reduce the amount of lost storage space to a minimum the above mentioned load engaging and carrying attachment has been devised which permits the use of aisles only slightly wider than the truck width.

It is therefore a general object of this invention to provide a load carrying device, suitable for use with the ordinary lift truck, which is adapted to pivot about the lifting member of the truck.

Another object of this invention is the provision of a load engaging and lifting member which is pivotally mounted on the lifting element and rotated by suitable power means controlled from the truck.

A still further object of this invention is the provision of a load engaging and lifting member which is pivotally mounted and has means for allowing the interchanging of the load engaging members in accordance with the various types of loads to be handled.

Other objects will become apparent from the following description and drawings wherein:

Fig. 1 is a side elevation of a lift truck with the load carrying attachment of the present invention mounted thereon;

Fig. 2 is a horizontal section along line 2—2 of Fig. 1 showing the load engaging members and the operating means for oscillating them;

Fig. 3 is a vertical section along line 3—3 of Fig. 2 showing details of the supporting means;

Fig. 4 is a front view of the device positioned to engage a bale; and

Fig. 5 is a fragmentary horizontal section along

2

line 5—5 of Fig. 3 showing details of attachment of the power means to the crank member of the device.

In general this device comprises a vertical bracket having a lower horizontal extension acting as a load bearing surface; a pair of bearing blocks vertically spaced on this bracket to act as guides for a pivotally mounted vertical rod member whose lower end rests on the aforementioned load bearing surface. A pair of angularly displaced load engaging members extend generally horizontally from the lower portion of the vertical rod, while a single member extends outwardly from the upper end centrally above the angular pair. This unit is mounted on any ordinary lift truck carriage assembly and is oscillated by means of an appropriately mounted double acting hydraulic cylinder.

Referring to the drawings, in Fig. 1, there is shown an ordinary lift truck designated as 1 having a conventional lift carriage unit 2 on which is mounted the device of the invention noted as 3.

The lift carriage 2 as best shown in Figs. 3 and 4 comprises a rectangular frame including horizontal elements 4, 5 and 6 connected by side verticals 7 and intermediate verticals 8, all being apertured near their upper ends to receive a mounting rod 9.

The load engaging and supporting member which is the subject of the invention is mounted on this lift carriage and as shown in Figs. 2, 3, 4 and 5 comprises a vertical bracket 10 having a lower horizontal extension 11 which acts as a load bearing member. A pair of bearing block assemblies 12 and 14 extend horizontally from the bracket 10, parallel to member 11. A flange-like portion 15 on the upper back side of bracket 10 is apertured to receive mounting rod 9 so as to secure the load engaging unit 3 to the lift carriage 2. This bracket is secured at its lower end by means of bolts 13 through cross piece 6.

The bearing blocks 12 and 14, and bearing surface 11 act to hold and pivot rod assembly 16 in position. This assembly 16 comprises upper and lower aligned sections 21 and 17 spaced apart and having their adjacent ends fitted with confronting crank discs 20 and 18 which are in turn held in spaced relation by bolt and spacer assemblies 22.

A pair of holders 23 and 24 are mounted on the lower portion of rod 17 and are maintained in spaced angular relation by means of brace 25 between them. Load engaging members 26 are adjustably secured in the hollow ends of holders 23

and 24 by suitable means such as set screws. It will also be noted that each holder 23 and 24 has a flange-like member 27 secured to its outboard side. These members are adapted to abut cross piece 6 for limiting the oscillating movement. A single holder 28 is mounted on the upper portion of rod 21 and carries a removable prong-like member 29 at its outer extremity. This is the principal load carrying member and is braced at 28'.

A double acting hydraulic cylinder 30 has one end pivotally mounted on bracket 31 which is in turn bolted to cross piece 5 of the frame. The outer end 34 of piston rod 32 is connected to crank pin 33 extending between discs 18 and 20. Tubes 35 and 36 carry the actuating fluid to the hydraulic cylinder from any ordinary hydraulic pump and control means normally used in such arrangements.

It should be noted that load engaging members 26 and 29 are removable from their holders and it is contemplated that various other types of load engaging members may be used depending on the type of materials being handled.

The operation of this load engaging device appears obvious but a brief reference to the operation will be made in connection with the stowing of bales of cotton in a warehouse.

The bale which is to be stored is grasped by load engaging members 26 and 29 sticking into the material a sufficient amount to firmly hold the bale. This bale is then lifted and carried to the location where it is to be stowed. The truck proceeds down the aisle until the desired site is reached, whereupon the load is raised or lowered to the correct height and by appropriate controls cylinder 30 is furnished fluid to actuate rod 32 and thereby rotate the bale handling device either to the right or left so that the bale may be deposited in the correct spot, after which the handling device is freed from the bale and the truck moves out of the aisle.

The details of construction of this particular embodiment of the invention here illustrated and described are not to be taken as limiting the scope of the invention since the device could be constructed in many forms.

What I claim as novel and wish to secure by Letters Patent is:

1. A load engaging and handling attachment suitable for the lift carriage of a commercial lift truck comprising a support, a load bearing member extending from the lower portion of said support, a pair of bearing blocks on said support, a rod assembly oscillatably carried by the aforesaid bearing blocks and load bearing member including separate upper and lower sections, crank discs mounted on the confronting ends of said sections and means spacing and fastening the discs together, a holder extending from the upper section and a pair of spaced holders extending from the lower section, load engaging elements extending from said holders, and

power means mounted on the lift carriage engageable with one of the disc spacing means to oscillate the rod assembly.

2. A load engaging and handling attachment suitable for the lift carriage of a commercial lift truck comprising a support, a member extending from the lower extremity of said support to act as a thrust bearing, a pair of guide bearings mounted on said support, a rod assembly carried by said bearings and including a lower section, a pair of laterally spaced rod-like holders extending outwardly from the lower portion of said section, a flange-like stop member positioned on the outward side of each holder, a crank disc secured to the top of said lower section, an upper section, a crank disc secured to the lower end of said upper section, a rod-like holder extending from the upper portion of said upper section, crank pin and spacer means connecting aforementioned discs in spaced relation, power means mounted on the lift carriage and having a rod engageable with said crank pin to rotate the rod assembly.

3. The device as described in claim 2 in which the upper rod-like holder is centrally above the spaced lower rod-like holders on the lower section.

4. A load engaging and handling attachment suitable for the lift carriage of a commercial lift truck comprising a support, means for attaching the support to said carriage, load bearing and guide means extending from said support, a rod assembly including separate upper and lower rod sections, crank discs mounted on the confronting ends of said sections, means spacing and fastening the discs together, a single load engaging member extending from one section and a pair of spaced load engaging members extending from the other section, and actuating means extending between the lift carriage and a crank disc spacing means to oscillate the rod assembly.
